INVENTOR.
Louis Grzosko
BY George C. Henricke
ATTORNEY

UNITED STATES PATENT OFFICE.

LOUIS GRZOSKO, OF AUBURN, NEW YORK.

RAIL JOINT.

1,427,287.

Specification of Letters Patent. Patented Aug. 29, 1922.

Application filed May 12, 1922. Serial No. 560,326.

To all whom it may concern:

Be it known that I, LOUIS GRZOSKO, a citizen of Poland, residing at Auburn, county of Cayuga, and State of New York, have invented certain new and useful Improvements in Rail Joints, of which the following is a specification.

This invention relates to improvements in railway rails, and particularly to improvements in rail joints, and it is the principal object of the invention to provide a rail joint which will positively connect the ends of two adjoining rails in a novel manner.

Another object of the invention is to provide a rail joint comprising a novel construction of the fish-plates for firmly connecting the adjoining ends of two rails to prevent positively a loosening of the connection under the pounding of the wheels of a train of cars passing over the rail heads.

These and other objects and advantages of my invention will become more fully known as the description thereof proceeds, and will then be more specifically pointed out in the appended claims.

In the accompanying drawing, forming a material part of this disclosure:

Figure 1 is a side view of a rail joint constructed according to the present invention. Figure 2 is a cross-section through one of the rails and fish plates on line 2—2 of Figure 1.

Figure 3 is a cross section on line 3—3 of Figure 1.

Figure 4 is a fragmentary side view of the end of one of the rails forming the joint.

Figure 5 is a side view of one of the fish plates.

Figure 6 is a cross section through the same along line 6—6 of Figure 5.

Figure 7 is a top plan and side view of the other of the fish plates co-operating with the fish plate illustrated in Figure 5.

Figure 8 is a cross section through the fish plate, Figure 7 on line 8—8, Figure 7.

Figures 9, 10, 11 and 12 are detail views of locking elements used to complete the joint.

The adjoining ends of two rails 10 and 11 provided with the customary heads 12 and foot flanges 13 are each provided with two square holes 14 for the passage of the dove-tailed ends 15 of a plurality of locking bolts 16 which are driven from one side of the

rail through a fish plate 17 provided for this purpose with a plurality of openings 18.

The dove-tailed ends 15 of the bolts 16 are passed through the openings 14 in the rail webs into sockets 19 in the second fish plate 20.

The sockets 19 communicate with dove-tailed recesses 21 in the upper edge of fish plate 20 adapted to receive wedge shaped dogs 22 engaging with their lower edges the shoulders of the ends 15 of bolts 16, when the fish plates are in operative position on both sides of the webs of the rails.

Fish plates 20 are provided with vertical channels 23 between two of the sockets 19, adapted to slidably receive locking members 24 entered from top and from the bottom, the central meeting edges of which are bevelled and adapted to be engaged by the bevelled end of operating elements 25 entered through transversely arranged square holes 26 on the inner face of fish plate 20.

The device operates as follows:

If it is desired to form a joint between the meeting ends of the two rails 10 and 11, the ends 15 of the bolts 16 are passed through the openings 14 in the webs of the rails until fish plate 17 engages the rail webs on one side thereof. Then fish plate 20 is engaged with the rail webs on the opposite side so that the ends 15 will enter sockets 19. As previously the dogs 22 have been placed in recesses 21 and locking members 24 in sockets 23 from above and below, while elements 25 are introduced into holes 26 with their bevelled ends in engagement with the meeting ends of member 24, the fish plate 20 will now be hammered into place so that dogs 22 will engage with their upper ends the underside of the rail heads 12 and will be forced into engagement with the ends 15. The engagement of the inner ends of elements 25 with the rail web will force these elements into engagement with the meeting ends of locking members 24 which will be driven asunder with their outer ends into engagement with sockets 27 in the underside of the rail heads 12 and sockets 28 in the upper faces of the rail flanges 13, so that an extremely secure connection between the two rails 10 and 11 is established.

It will be clear that changes may be made in the general arrangement of my device and in the construction of the minor details

thereof without departing from the scope and spirit thereof.

Having thus described my invention, what I claim as new, and desire to secure by Letters Patent of the United States is—

1. A rail joint of the class described, comprising two fish plates adapted to engage opposite sides of the webs of two adjoining perforated rail ends, bolts passed through 10 one of said fish plates, dove-tailed ends on said bolts adapted to be passed through the perforations in said rail ends into engagement with sockets in the second of said fish plates, said sockets communicating with upper recesses, means slidably held in these recesses for engaging the dove-tailed ends of said bolts by engagement with the rail head when said second fish plate is hammered home, and means for locking said second fish 20 plate automatically to the rail head and the flange upon the engagement of said bolts and said sliding means.

2. A rail joint of the class described, comprising two fish plates adapted to engage opposite sides of the webs of two adjoining perforated rail ends, bolts having dove-tailed shaped ends integral with one of said fish plates adapted to be passed through the perforations of said rail ends into sockets in 30 the second of said fish plates, sliding blocks in recesses in the upper edge of said second fish plate communicating with said sockets and adapted to engage the underface of the rail heads to be driven into engagement with 35 said dove-tail ends of said bolts when said

second fish plate is hammered into web engaging position, said second fish plate provided with vertical and transverse channels, means in said vertical channels adapted to engage recesses in the rail heads and flanges, and means in said transverse channels adapted to engage said first named means to lock it in position upon the hammering home of said second fish plate.

3. In a rail joint of the class described, the combination of two fish plates, locking bolts on the inner face of one of said fish plates adapted to be passed through the rails into engagement with the second fish plate, said second fish plate recessed in its upper edge, sliding blocks in said recesses adapted to engage the underside of the rail head to be forced into engagement with the ends of said locking bolts, a pair of locking bolts having inner bevelled meeting ends movably disposed in a vertical channel of said second fish plate, and an operating member having a bevelled end adapted to be passed through a transverse opening in said second fish plate into engagement with the meeting ends of said bolts to drive their outer ends into recesses in the lower face of the rail head and the upper face of the rail flanges to lock the parts in their adjusted position upon the hammering of said second fish plate into engagement with the rail web.

In testimony whereof I have affixed my signature.

LOUIS GRZOSKO.
